UNITED STATES PATENT OFFICE.

ROBERT L. DORAN, OF CHICAGO, ILLINOIS.

OIL BURNER.

Application filed June 24, 1925. Serial No. 39,290.

To all whom it may concern:

Be it known that I, ROBERT L. DORAN, a citizen of the United States of America, and a resident of Chicago, in the county of 5 Cook and State of Illinois, have invented a new and useful Improvement in Oil Burners, of which the following is a specification.

This invention relates to oil burners intended for continuous operation throughout 10 a season but provided with a thermostatic control device which regulates the burner to operate with either a low flame or a high flame according to changes in the temperature of the heated space.

15 The objects of the invention are to provide an improved burner of this type in order to always maintain a heated burner-head so that when the supply of fuel to the burner is increased up to the normal running 20 requirements, proper conditions for good combustion will exist. By this means some objections to intermittently operated oil burners are avoided. Assuming that efficient combustion does not take place until the fuel 25 is gasified and raised to the ignition temperature by heat, it is necessary to provide means for promptly heating the fuel as it arrives at the burner-head, otherwise operating conditions are inconstant to such an 30 extent that there is considerable escape of unconsumed fuel upon starting operations before sufficient heat is generated to gasify 35 the fuel as required for efficient combustion. Thus with intermittently operated burners without means for heating the initially discharged fuel, considerable time is required before proper conditions are brought about for efficient operation of the burner.

It is also the purpose of the invention to 40 provide an improved burner which operates by natural draft when burning low and utilizes a forced draft only when an increase in heat is required. It is also an object of the invention to provide improvements in 45 the valve operating means whereby the valve for controlling the supply of fuel may be shifted from a partially open position to a more fully open position when the burner changes over from the natural draft operation 50 to forced draft operation. A further purpose of the invention is to provide such a valve operating mechanism which automatically operates to permit the valve to move to fully closed position in case of 55 failure of correct operation of the burner.

The purposes of the invention are accom-

plished by a construction as illustrated in the drawings, in which:

Figure 1 is a plan view of the entire burner and operating mechanism therefor. 60

Figure 2 is a sectional detail of the burner-head taken on the line 2—2 of Figure 1.

Figures 3 and 4 are fragmentary side views of the construction shown in Figure 1.

Figure 5 is an end view taken from the 65 left of Figure 1.

Figure 6 is an enlarged detail partly in section of the valve operating means shown in Figure 5.

Figures 7 and 8 are fragmentary details 70 relating to automatic means for stopping the action of the burner as viewed in the direction indicated by arrows 7 and 8, Figure 6.

Figure 9 is a sectional detail of the fuel supply controlling valve and operating 75 means therefor taken on the line 9—9 of Figure 6.

Figure 10 is a plan view of the mechanism shown in Figure 9.

One main characteristic of the burner 80 herein described is that it operates under natural draft according to some predetermined minimum heat requirements, and changes over to forced draft and increased fuel supply as controlled by thermostats. The burner-head is always heated and the 85 change in conditions of operation is therefore not so extreme as with the intermittently operated burners wherein there is a sudden discharge of atomized fuel into a cold burner-head and proper operating conditions cannot be obtained until some time after starting an operation as it is necessary for the fuel to absorb a great quantity of 90 heat before it is properly conditioned for efficient combustion. Another feature of the improved construction is that the automatic means for stopping the operation of the burner, in case of failure of ignition, includes 95 a diaphragm for operating a shut-off valve and avoids the necessity of other forms of movable shut-off means which are liable to leak at a packing.

In carrying out the invention as illustrated in the drawings, fuel is supplied under pressure through conduit 1 (Figure 1) from which it flows through a valve housing 2 (Figure 9) past the valve 3 into diaphragm chamber 4 and from there through the passageway 5 to the conduit 6 leading to the burner. The valve 3 is urged toward its 100 closed position by a spring 7 but is normally 105 closed by a stop 8. The valve 3 is urged 110

prevented from closing by a cam 8 on a shaft 9. The setting of this valve determines the minimum flow of the fuel and when in this position the operation of the burner is simply the burning of this minimum supply of fuel as it leaves the outlet end 10 of conduit 6, the air being drawn into the burner-head 11 through the tube 12 surrounding the fuel conduit and communicating with a fan casing 13 having an air inlet opening 14. The burning of this minimum quantity of fuel under the natural draft created thereby furnishes a moderate quantity of heat and also serves to keep the burner 11 in a heated condition so that the fuel delivered thereto will rapidly vaporize, therefore, when the flow of fuel is increased to normal the operating conditions are not so bad as with a burner which is permitted to get cold at intervals between times of normal operation. The burner is under thermostatic control for the purpose of shifting valve 3 to its more open position when more heat is required. The thermostatic control apparatus is not illustrated in the drawings as it includes a standard construction of electromagnetic means under the control of a thermostat for turning on and off the switch of the motor. This electromagnetic means is included in casing 15 in which casing a switch is also mounted for controlling the operation of an electric motor 16 (Figure 3) for driving a blower 17. The switch operating means in casing 15 serves to rotate shaft 9 extending therefrom, 180 degrees at each operation. Thus when the thermostatic control means closes the motor switch by rotating shaft 9, 180 degrees from the zero position shown in Figure 9, the flat part 18 of cam 8 moves away from the nut 19 at the end of the stem of valve 3, and the higher circular part of the cam presses the nut inwardly and shifts the valve to its more open position, thus allowing a greater flow of fuel to the burner. At the same time motor 16 is started operating the fan within the blower housing 17 and forcing additional air through the tube 12 to the burner-head as required for efficient combustion at the increased rate of fuel supply. When the thermostatic control device effects another half turn of shaft 9 when the room temperature for which it is set is reached, flat part 18 of cam 8 comes opposite the nut 19 and the valve returns to its normal position, as shown in Figure 9, under action of its spring 7. The valve housing 2 is completely sealed at one end by plug 119 against which spring 7 seats and at the opposite end by a diaphragm 20 clamped to the valve housing by ring 21 and screws 22. The valve stem 23 has a shoulder 24 bearing against one side of the diaphragm and carries the nut 19 at its end, bearing against the opposite side of the diaphragm. The purpose

of the diaphragm 20 is to provide a means for communicating motion to the controlling valve 3 while avoiding the likelihood of leakage at the valve as would be the case if the stem of the same were movable through a packed bearing. Packing would likewise interfere with the free movement of the valve under the action of its spring.

The cam 8 is splined to shaft 9 as illustrated in Figure 6 so that the cam may rotate with the shaft 6 but still be capable of longitudinal movement along the key way 25. The purpose of this construction is to permit the cam to slide along the shaft 9, under certain conditions, entirely away from nut 19 on the end of the valve stem and thus permit the valve and diaphragm 20 to move to the right (Figure 9) where the valve becomes seated and prevents all flow of fuel from supply conduit 1 to the conduit 6 leading to the burner. The cam 8 is urged to slide away from the nut 19, along the shaft 9 by a spring 26 but is normally prevented from so moving by a rod 27 in the hollow end of shaft 9 and carrying a pin 28 passing through the key way 25 and bearing on the left side of cam 8. At its opposite end rod 27 bears against a knob 29 on the upper end of a vertical rod 30. This rod is held in the position in which it is shown in Figure 6 by a spring 31 bearing between the lower arm 32 of the bearing bracket 33 for rod 30, and a collar 34 secured to the rod by a set screw. A weight 35 is slidable along the rod 30 but normally held in its upper position by latch 36. If this latch is shifted away from beneath the weight 35, the latter drops and when it strikes collar 34 shifts the rod downwardly a sufficient extent to release rod 27, permitting it to move outwardly along the hollow part of shaft 9 under the action of spring 26 bearing against the cam 8 and through the cam 8 pressing against pin 28 of rod 27. Therefore when the rod 27 is released the cam 8 shifts entirely clear of nut 19 and permits the valve 3 to become seated. After the cam 8 is so shifted, any rotation of its shaft 9 by electromagnetic means within the controller 15 will not affect the position of valve 3 and therefore the oil burner cannot function.

The operation of the shut-off means is dependent upon unburned fuel draining back from the burner-head 11 into a cup 37 hung from the end of a lever 38. The cup 37 and lever 38 are normally held in the position indicated in Figure 3 by weight 39 at the opposite end of the lever. When this weight is overbalanced due to oil collecting in cup 37, the lever in rocking turns latch plunger 36 so that a pin 40 passing through the plunger registers with opening 31 in bearing bracket 33. The pin 40 is normally seated in a slot 43 (Figure 7) in boss 44 on the inner face of lever 38. This lever is pivot-

ally supported on the latch plunger 36. When the lever is overbalanced by the weight of oil collecting in cup 37 through the pin 40, it rocks the plunger 36 until the pin registers with the slot 41 in the bearing. Then the plunger moves away from the weight 35 under the action of its spring.

The lever 38 carries a mercury switch 45 (Figure 1) in the motor circuit so that when the lever rocks away from its normal position, the motor circuit will be opened irrespective of the position of other controlling switches therefor.

The burner-head 11 is constructed as shown in Figures 1 and 2 and is of cylindrical form and the flow of fuel and air through the conduits 6 and 12 is tangential to the cylinder in order to guide the fuel and air into a swirling path before the flame leaves the opening 46 in cover-plate 47 of the burner. The burner-head is also preferably provided with a conical inlet 48 surrounding the outlet of conduit 6 and forming a continuation of the tubular extension 49 connecting the burner-head with air conduit 12. The inlet member 48 is slightly offset at the bottom to provide a pocket 50 into which the fuel oil may drip and from which it is evaporated by the heat conducted thereto by the burner-head. If combustion is for any reason accidentally discontinued and the oil continues to drip into the member 48 it will first overflow from this member into the outlet 51 at the bottom of the tubular extension 49 of the burner. This outlet communicates with a drain pipe 52 having an outlet 53 over the cup 37. As soon as sufficient oil is collected in the cup, weight 39 is overbalanced and the operation of the burner discontinued as previously described. The conduit 53 is preferably provided with a branch 54 communicating with the bottom of the burner-head 11 in order to drain away any fuel oil should the same collect at this point.

The maximum supply of fuel is controlled by valve 55 (Figure 1) and the normal wide-open position of valve 3 would ordinarily allow the maximum flow of fuel permitted at 55. The minimum supply is regulated by the normal setting of valve 3. This may be effected by adjusting the cam shaft 9 toward and away from nut 19 by means of the screw 57 (Figure 10) operating against the action of spring 58 pressing against bearing 60 of the shaft.

The collar 61 on the shaft 9 affords a convenient means for restoring the cam 8 and rod 27 in case of an operation of the automatic shut-off means.

When the device is first set up and charged with fuel, it is desirable to release the air from diaphragm chamber 4 and allow this to completely fill up with oil. This is done by shutting off valve 55 and

unscrewing the air vent 56 (Figures 9 and 10).

In the operation of the device minimum heat requirements are provided for by adjustment through screw 57 of valve 3 which is normally held from its seat by cam 8 as indicated in Figure 9 with the flat part of the cam opposite nut 19. Fuel flows from supply conduit 1 past valve 3 and into the conduit 6 to the burner-head and is vaporized in the burner by heat conducted thereby and the heat radiated from the flame. The air supply is drawn through the conduit 12 by the natural draft created by combustion. If the thermostatic control means operates to turn on the motor by rotating shaft 9 one hundred and eighty degrees, a high portion of cam 8 presses against nut 19 and shifts valve 3 to its wideopen position, thus allowing a maximum flow of fuel as determined by the setting of valve 55 (Figure 1). The additional air required is then forced through the conduit 12 by the blower 17. When the thermostatic control device again turns the shaft 9 so that the flat part of cam 8 comes opposite nut 19 the minimum fuel flow restored and at the same time the motor circuit is opened by the thermostatic control means.

In a case of failure of combustion, the oil, dripping into the bottom of the burner-head or into the conical part 38 thereof, is drained out of the burner-head into cup 37 by conduit 52. The overbalancing of lever 38 by the weight of the oil in the cup results in this lever oscillating the latch plunger 36 so that its pin 40 registers with the slot 41 and the plunger springs away from the weight 35 allowing this weight to strike collar 34 on the rod 30 and lower the latter away from the rod 27. Then the cam 8 and the rod 27 are projected outwardly by spring 26 and valve 3 seats under the action of its spring 7. The motor circuit is opened by the rocking of lever 38.

Although but one specific embodiment of this invention has been herein shown and described, it will be understood that numerous details of the construction shown may be altered or omitted without departing from the spirit of this invention as defined by the following claims.

I claim:

1. In a burner of the class described, a cylindrical burner-head closed at the bottom and having an opening at the top of less diameter than the diameter of the burner-head, and a fuel and air inlet entering the side of the burner-head in a tangential direction in order to produce a swirling motion of the fuel and air within the burner-head and to the flame, said fuel and air inlet comprising a conduit for air and a conduit for fuel inside the air conduit, said air conduit terminating in a nozzle gradu-

ally reduced in diameter toward its discharge end, said nozzle being formed to provide a receiving pocket for the unatomized fuel at its lower side, a fuel operated shut-off device for the fuel, and a conduit leading from said pocket to said fuel operated shut-off device.

2. An oil burner comprising a burner-head, fuel and air conduits leading thereto, 10 a valve for controlling the flow of fuel through the fuel conduit, said valve being movable from a position where it permits a predetermined minimum flow to a position where it permits a predetermined maximum 15 flow of fuel, thermostatically operated means for shifting said valve from one position to another, a motor driven fan for forcing air through said air conduit, and said thermostatically operated means being 20 arranged to control the operation of said motor driven fan whereby the fan is operated when the valve is in position for maximum flow and is stopped when the valve is in position for minimum flow, the means 25 for operating said valve including a diaphragm cooperating with the stem of the valve and a cam for shifting said diaphragm.

3. A liquid fuel burner of the class described comprising a burner-head, means 30 for delivering fuel and air under pressure to said burner-head, a valve for controlling the flow of fuel, said valve being movable within a casing and said casing being sealed by a diaphragm coacting with said valve, 35 a cam for shifting said diaphragm, thermostatically controlled means for operating said cam, a spring opposing the action of said cam and normally urging said valve toward its seat, and means dependent for 40 operation upon failure of combustion for shifting said cam into inoperative position, whereby said spring may act to seat the valve.

4. A liquid fuel burner of the class described comprising a burner-head, means 45 for delivering fuel and air under pressure

to said burner-head, a valve for controlling the flow of fuel, said valve being movable within a casing and said casing being sealed by a diaphragm coacting with said valve, 50 a cam for shifting said diaphragm, a spring opposing the action of said cam and normally urging said valve toward its seat, and means for shifting said cam into inoperative position whereby said spring may 55 act to seat the valve, said means comprising a spring for shifting said cam, means for normally preventing the operation of said spring, said means comprising a vertical rod mounted for motion in the direction of its length and a spring for normally holding the rod in its upper position, a weight 60 slideable along said rod, means normally retaining the weight against movement downwardly along the rod; a collar on the rod which may be engaged for the purpose of 65 shifting the rod to releasing position when said weight is released, means for shifting said weight retaining means to releasing position, said means including a lever and a cup hung from said lever and adapted to overbalance the same by the weight of the fuel collected in said cup.

5. A liquid fuel burner comprising a burner-head and fuel and air feeding means, a valve for controlling the feed of fuel and a shut-off mechanism for said valve, said shut-off mechanism including a releasable weight and connections for permitting the valve to move to closed position, a plunger 70 normally retaining said weight against motion, a spring for shifting said plunger to releasing position, means retaining said plunger against operation comprising a pivoted lever from which is hung a fuel collecting cup, said lever being dependent for 75 operation upon the weight of the fuel in the cup.

Signed at Chicago this 22nd day of June, 1925.

ROBERT LAWRENCE DORAN.
